[57] CLAIM

The ornamental design for a "travel pillow", as shown and described.

DESCRIPTION

FIG. 1 is a perspective view of the cushion portion of a travel

pillow, showing my new design, for convenience of illustration;

FIG. 2 is a fragmentary exploded perspective view;

FIG. 3 is a perspective view of the travel pillow;

FIG. 4 is a front elevational view of the cushion portion for convenience of illustration;

FIG. 5 is a end elevational view of the cushion portion for convenience of illustration, the opposite end being identical thereto;

FIG. 6 is a top plan view of the cushion portion for convenience of illustration;

FIG. 7 is a bottom plan view of the cushion portion for convenience of illustration;

FIG. 8 is a front elevational view of the cushion portion, in an alternate configuration for convenience of illustration; and,

FIG. 9 is a top plan view of the cushion portion, in an alternate configuration for convenience of illustration.

The bottom of the pillow is plain and unornamented.
